UNITED STATES PATENT OFFICE.

EDWARD HAMMANN, OF BROOKLYN, ASSIGNOR TO THE J. L. MOTT IRON WORKS, OF NEW YORK, N. Y.

DESIGN FOR A LAVATORY-LEG.

SPECIFICATION forming part of Design No. 22,689, dated August 8, 1893.

Application filed June 19, 1893. Serial No. 478,174. Term of patent 7 years.

To all whom it may concern:

Be it known that I, EDWARD HAMMANN, a citizen of the United States, residing at Brooklyn, in the county of Kings and State of New York, have invented a new Design for a Metallic Leg for Lavatories and Sinks, of which the following is a specification.

The leading feature of this design for a metallic leg consists in the design of the body which is cylindrical and corrugated vertically and has a cylindrical molded base and tapering lower end.

In the drawings:—Figure 1, is an elevation of the leg and Fig. 2, is a sectional plan at the line *x*. *x*.

Below the curved upper end *a*, and the

polyagonal capital *f*, is the vertical body *h* ornamented with a series of longitudinal corrugations, and at *i*, is a cylinder with a molding *g*, and a tapering bottom part *k*, to the 20 leg. The extreme bottom end of the leg may be at the end of the taper *k*, as shown, or a claw and ball may be provided as indicated by dotted lines.

I claim—

The design for a metallic leg substantially as described and represented.

Signed by me this 16th day of June, 1893.

EDWARD HAMMANN.
